SAILBOAT HULL

Hobart L. Alter, Capistrano Beach, Calif., assignor to
Coast Catamaran Corporation, San Juan Capistrano,
Calif.

Filed Jan. 24, 1972, Ser. No. 220,542

Term of patent 14 years

Int. Cl. D12—06

U.S. Cl. D12—70

FIG.1

FIG.2

FIG.3

FIG.4

FIG.5

FIG.7

FIG.6

FIG. 1 is a perspective view of a sailboat hull showing my new design;

FIG. 2 is a top plan view of said sailboat hull;

FIG. 3 is a side elevational view showing the right-hand side of said sailboat hull;

FIG. 4 is a side elevational view of the left-hand side of said sailboat hull;

FIG. 5 is a bottom view of said sailboat hull;

FIG. 6 is a rear view of said sailboat hull; and

FIG. 7 is a front view of said sailboat hull.

The surface characteristic partially shown in FIGS. 1 and 2 is understood to be continuous within the borders shown.

I claim:

The ornamental design for a sailboat hull, substantially as shown and described.
